UNITED STATES PATENT OFFICE

2,431,521

GUM BRACE

Julius A. Thiemann, New York, N. Y.

Application June 22, 1946, Serial No. 678,599

10 Claims. (Cl. 128—260)

1

The present invention concerns an article of manufacture designed to be worn in the mouth between the gums and the lips for the purpose of advantageously altering the facial contour and to act as a gum brace.

It is well known that a youthful facial appearance requires a firm and smooth surface of the skin, unbroken by wrinkles or depressions which are the accompaniment of wasted tissues, missing teeth and so forth.

An object of the present invention is the provision of a device to support the facial tissue from the interior of the mouth, the device itself resting in the space between the gums and the upper or lower lips.

A further object is that such a device be light in weight, readily removable, sanitary and comfortable to wear.

It is a further object of the invention that such a device comprise means for the retention of an antiseptic and deodorant substance.

Still another object is that a device of the character described shall be so cheaply fabricated as to be disposable after a certain period of use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a blank from which the device of the present invention is fabricated.

Fig. 2 is a perspective view of the device embodying the invention.

Fig. 3 is an enlarged sectional view taken on the line 3—3 of Fig. 2.

Fig. 4 is a top plan view of the device.

Referring now in detail to the drawings, Fig. 1 illustrates the blank 10 from which the oral appliance of the invention is made as hereinafter described. The blank 10 comprises an elongated body with a straight side 11 and end boundaries 12 and 13 substantially perpendicular therewith to form square corners. The opposite side boundary of the blank curves inwardly as at 14 to define a longitudinally central portion 15 which is relatively narrow, and curves outwardly therefrom toward both ends to define relatively broad wing portions 16 and 17, curving again inwardly as at 18 and 19 to merge with the squared end portions 12 and 13.

2

In Fig. 2, the blank has been bent and the appliance now comprises the generally elongated and U-shaped piece 20, the central portion 15 of which is identical with the relatively narrow central portion 15 of blank 10, and comprising a single thickness of material. Portion 15 is the central portion of the continuous portion 15^a, 15, 15^b extending the length of piece 20 and being the same substance as shown on the one side 10 of dotted line 21 of Fig. 1. This portion 15^a, 15, 15^b constitutes the interior wall of piece 20, the wing portions 16 and 17 of Fig. 1 becoming exterior wall portions 16 and 17 of Fig. 2, formed by gently bending wing portions 16 and 17 substantially along line 21 so that the end portions 22 and 23 of piece 20 are hollow and of substantially U-cross section as clearly shown in Fig. 3.

The terminal portions of the respective exterior and interior walls 16, 15^a and 15^b, 17 are brought together and firmly joined conveniently, as shown by an adhesive and protective coating 24 of hard rubber or similar material.

Pads 25 of absorbent material such as hospital cotton or the like are inserted between walls 16, 15^a and 15^b, 17 and compressively retained. Pads 25 are useful for retaining within the mouth any desired antiseptic or deodorant material or medication.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A blank for an oral appliance, said blank 40 comprising a piece of bendable sheet material, said piece being of generally elongated shape and comprising one substantially straight side boundary terminating at each end in substantially square corners, the other side boundary being 45 curved inwardly at the central portion of said piece and outwardly at the end portions, said end portions further being inwardly curved to merge with said square corners.

2. A blank for an oral appliance, said blank 50 comprising a piece of bendable sheet material, said piece being of generally elongated shape and comprising one substantially straight side boundary terminating at each end in substantially square corners, the other side boundary being 55 curved inwardly at the central portion of said

piece and outwardly at the end portions to a width substantially double the width of said central portion, said end portions further being inwardly curved to merge with said square corners.

3. An oral appliance for improving facial contour comprising an elongated piece of bendable material conforming generally to the exterior outline of the human gum, said piece comprising a single thickness at its central portion and exteriorly extending integral wing portions at its ends.

4. An oral appliance for improving facial contour comprising an elongated piece of bendable material conforming generally to the exterior outline of the human gum, said piece comprising a single thickness at its central portion, and wing portions at its ends, said wing portions extending integrally and exteriorly from said central portion to constitute hollow portions of substantially U-cross section.

5. An oral appliance for improving facial contour comprising an elongated piece of bendable material conforming generally to the exterior outline of the human gum, said piece comprising a single thickness at its central portion and wing portions at its ends, said wing portions extending integrally and exteriorly from said central portion to constitute hollow portions of substantially U-cross section, the terminal portions of said hollow portions having their walls brought together and joined.

6. An oral appliance for improving facial contour comprising an elongated piece of bendable material conforming generally to the exterior outline of the human gum, said piece comprising a single continuous interior wall extending throughout the length thereof, said interior wall constituting the central longitudinal portion of said piece, said piece further comprising exterior wall portions extending from said interior wall portion longitudinally beyond said central wall portion to form end portions of substantially U-cross section.

7. An oral appliance for improving facial contour comprising an elongated piece of bendable material conforming generally to the exterior outline of the human gum, said piece comprising a single continuous interior wall extending throughout the length thereof, said interior wall constituting the central longitudinal portion of said piece, said piece further comprising exterior wall portions extending from said interior wall portion longitudinally beyond said central wall portion to form end portions of substantially U-cross sec-

tion, said exterior and interior portions further being joined together at the ends thereof.

8. An oral appliance for improving facial contour comprising an elongated piece of bendable material conforming generally to the exterior outline of the human gum, said piece comprising a single continuous interior wall extending throughout the length thereof, said interior wall constituting the central longitudinal portion of said piece, said piece further comprising exterior wall portions extending from said interior wall portion longitudinally beyond said central wall portion to form end portions of substantially U-cross section, and means joining said interior and exterior wall portions together at the ends thereof.

9. An oral appliance for improving facial contour comprising an elongated piece of bendable material conforming generally to the exterior outline of the human gum, said piece comprising a single continuous interior wall extending throughout the length thereof, said interior wall constituting the central longitudinal portion of said piece, said piece further comprising exterior wall portions extending from said interior wall portion longitudinally beyond said central wall portion to form end portions of substantially U-cross section, and a wad of absorbent material located between said interior and exterior wall portions.

10. An oral appliance for improving facial contour comprising an elongated piece of bendable material conforming generally to the exterior outline of the human gum, said piece comprising a single continuous interior wall extending throughout the length thereof, said interior wall constituting the central longitudinal portion of said piece, said piece further comprising exterior wall portions extending from said interior wall portion longitudinally beyond said central wall portion to form end portions of substantially U-cross section, and a wad of absorbent material located between said interior and exterior wall portions at each end of said appliance.
